UNITED STATES PATENT OFFICE.

WILLIAM KETCHUM JONES, OF WICHITA, KANSAS.

UNION GARMENT.

1,170,272.

Specification of Letters Patent.

Patented Feb. 1, 1916.

Application filed June 11, 1915. Serial No. 33,572.

To all whom it may concern:

Be it known that I, WILLIAM K. JONES, a citizen of the United States, residing at Wichita, in the county of Sedgwick and State of Kansas, have invented certain new and useful Improvements in Union Garments, of which the following is a specification, reference being had to the accompanying drawings.

10 This invention relates to certain improvements in union garments and has relation more particularly to a garment of this general character wherein are combined overalls and jacket; and it is an object of my invention to provide a novel and improved garment of this general character wherein the jacket is provided at its back with a depending skirt adapted to overlie the seat flap of the garment and adapted to be secured to said seat flap independently of the fastening means for maintaining the seat flap in closed adjustment.

15 The invention consists in the details of construction and in the combination and arrangement of the several parts of my improved union garment whereby certain important advantages are attained and the device is rendered simpler, less expensive and otherwise more convenient and advantageous 20 for use, all as will be hereinafter more fully set forth.

The novel features of the invention will be carefully defined in the appended claim.

25 In order that my invention may be the better understood, I will now proceed to describe the same with reference to the accompanying drawings, wherein—

30 Figure 1 is a view in perspective illustrating a union garment constructed in accordance with an embodiment of my invention in applied position; and Fig. 2 is a perspective view of my improved garment with the seat flap in open adjustment and the skirt of the jacket lifted.

35 The device as herein disclosed is an improvement over the garment disclosed in my co-pending applications, Serial No. 836,458, filed May 5, 1914, and resulting in Patent No. 1,142,580 dated June 8, 1915, and Patent No. 1,145,771, dated July 6, 1915, and certain of the parts of my invention herein disclosed are more particularly described and claimed in the aforesaid patents.

40 As herein disclosed, 1 denotes the body

portion or jacket of my improved garment and 2 the nether portion or overalls and 3 denotes the seat flap of the garment adapted to be maintained in closed adjustment through the medium of the fastening members 4 carried thereby and adapted to coact with the button-holes 5 arranged along each of the side openings 6.

45 The back 7 of the jacket or body portion of my improved garment is provided with the depending skirt 8 adapted to overlie the seat flap when in closed adjustment and of a width less than the width between the side seams or openings 6 of the nether portion of the garment and the free corners of said skirt are provided with the button-holes 14 adapted to coact with the fastening members 9 secured to the seat flap adjacent the lower extremity thereof and at a point intermediate the side seams or openings 6 and the hip pockets 10 whereby it will be readily 50 observed that the depending skirt may be effectively secured to or released from the flap without the necessity of interfering in any way with the fastening means for maintaining the seat flap in closed adjustment. 55 It will also be perceived that by buttoning the skirt 8 between the side openings 6 and the hip pockets 10, the user has the advantage of having the flap or skirt button down and at the same time has free access to the 60 side openings, and it is to be further observed that the fastening members 9 are so positioned as not to interfere with the 65 pockets.

70 The back 7 has suitably secured thereto the suspender member 11 with which is adapted to be detachably engaged the tab 12 carried by the seat flap 3 in order to maintain said seat flap in proper closed adjustment.

75 From the foregoing description, it is thought to be obvious that a union garment constructed in accordance with my invention is of an extremely simple and comparatively inexpensive nature and is particularly well 80 adapted for use by reason of the convenience and facility with which it may be assembled, and it will also be obvious that my invention is susceptible of some change and modification without material departure from the 85 principles and spirit thereof and for this reason I do not wish to be understood as 90 limiting myself to the precise arrangement 95

and formation of the several parts herein shown in carrying out my invention in practice.

I claim:

- 5 A union garment comprising a body portion and a nether portion, said nether portion being provided with a seat opening, and a seat flap provided with a pocket and the jacket portion provided at its back with a
- 10 depending skirt adapted to overlie the seat flap and the mouth of the pocket, said skirt being of a width less than the width of the seat opening and having its sides terminating inwardly of and in spaced relation relatively to the side slits of the nether portion as afforded by the seat opening, fastening
- 15

means for the seat flap, and co-acting fastening means carried by the seat flap adjacent its inner end and between the pocket and the sides thereof, at points below the top 20 of the pocket and by the skirt adjacent its free corners, whereby said skirt may be secured to the flap in overlying relation, said co-acting fastening means being independent of the fastening means for the seat flap. 25

In testimony whereof I hereunto affix my signature in the presence of two witnesses.

WILLIAM KETCHUM JONES.
